UNITED STATES PATENT OFFICE.

GEORGE WALTER HAWKINS, OF PROVIDENCE, RHODE ISLAND.

FLAT-IRON HOLDER AND WAXER.

1,140,265.

Specification of Letters Patent.

Patented May 18, 1915.

Application filed August 3, 1914. Serial No. 854,758.

To all whom it may concern:

Be it known that I, GEORGE W. HAWKINS, a citizen of the United States, residing at Providence, in the county of Providence, 5 State of Rhode Island, have invented certain new and useful Improvements in Flat-Iron Holders and Waxers; and I do hereby declare the following to be a full, clear, and exact description of the invention, such as 10 will enable others skilled in the art to which it appertains to make and use the same.

This invention relates to laundry devices, particularly to iron holders, and has for its object the provision of a novel device adapted to be clamped upon an ironing board for holding the iron.

An important object is the provision of an iron holding stand provided with means whereby the iron may be waxed.

20 Another object is the provision of a device of this character which will be simple and inexpensive in construction, efficient and durable in use and a general improvement of the art.

25 These and other objects and advantages will be carefully brought out in the following description and illustrated in the accompanying drawing, in which—

Figure 1 is a side elevation of an ironing board showing my device applied thereto, Fig. 2 is an enlarged fragmentary sectional view therethrough, showing my device in side elevation, Fig. 3 is a plan view of my device detached, and Fig. 4 is a longitudinal sectional view therethrough.

Referring more particularly to the drawing the numeral 5 designates an ironing board of any well known or preferred type to which my device is adapted to be secured.

40 My device comprises a U-shaped bracket 6 having its upper arm 7 adapted to be disposed upon the top of the ironing board 5 and having its lower arm 8 provided with a screw threaded aperture for the passage of a clamping screw 9 having a wing head 10 and provided with a swivel end 11. The bracket 6 being placed in position upon the ironing board, turning the clamping screw 9 will clamp the bracket upon the board.

50 Formed upon the upper end of the bracket 6 is an ear 12 to which is pivoted, as shown at 13, ears 14 formed on a flat plate 15 sup-

ported upon lugs 16 which may be cast upon or stamped from the material of the plate. The plate 15 is adapted to support an iron 55 which is prevented from accidental displacement by upstanding projections 17 arranged at the sides of the plate 15. The plate 15 may be provided with cutout portions 18 in order to reduce its weight. In order that an 60 iron may be waxed, I provide the plate 15 with a recess 19 within which is disposed a block of wax 20, the upper edge of which extends above the surface of the plate 15.

When the bracket 6 is clamped upon the 65 ironing board 5 as previously described, the plate 15 will be disposed over the board with the lugs 16 resting upon the top of the board. The iron to be held is slid onto the plate 15 from the end toward the bracket and can be 70 removed therefrom by merely lifting it vertically or slid back off the plate 15 thus waxing it upon its engagement with the block of wax 20.

From the foregoing description and a 75 study of the drawing it will be apparent that I have thus provided a novel and simple attachment for an ironing board whereby an iron may be conveniently held or waxed.

80

It will be readily understood that I reserve the right to make various changes in the form, construction and arrangement of parts without departing from the spirit of the invention or limiting the scope of the 85 subjoined claim.

Having thus described my invention, I claim.

An iron holding attachment for an ironing board, comprising a clamp engageable upon 90 the ironing board, an ear formed on said clamp, a flat plate having ears pivoted upon said first named ear, lugs on the lower side of said plate and resting upon the top of the board, and upstanding projections at the 95 edges of said plate for preventing displacement of an iron disposed thereon.

In testimony whereof, I affix my signature, in the presence of two witnesses.

GEORGE WALTER HAWKINS.

Witnesses:

EDWARD M. PIERCE,
CHARLES R. CHRISTIE.
